UNITED STATES PATENT OFFICE.

CARL ABSMEIER, OF MAYWOOD, ILLINOIS.

PLASTER BOARD.

REISSUED

Application filed November 23, 1925, Serial No. 70,765. Renewed November 10, 1927.

This invention relates to plaster board and is more particularly concerned with a novel construction of covering for the body of the board and a novel interlocking means 5 of joining the covering sheets of fibrous material which are used to cover the plaster body at the edges of said board. In the making of plaster board it is common practice to make a body of cementitious material, usually a plaster of Paris composition, which is covered on opposite sides with fibrous material, usually a certain type of paper. The edges of the board are sometimes left uncovered and in other cases are 10 covered in various manners. My invention is directed particularly to a new edge covering for plaster board which comprises interlocking tongues on opposite pieces of paper covering for the opposite sides of the plaster board which are turned inwardly toward each other and are bent under the adjacent inwardly turned or edge portions of the paper covering making a secure and interlocking connection of the opposite covering 15 sheets for the plaster board at the edges thereof.

Constructions which embody my invention are fully shown in the accompanying drawing, in which,

30 Fig. 1 is a fragmentary perspective view showing opposed covering sheets for the body of plaster, the same being separated.

Fig. 2 is a fragmentary perspective view of an edge of the plaster board which has 35 been covered.

Fig. 3 is a fragmentary transverse section through the construction shown in Fig. 2.

Fig. 4 is a view similar to Fig. 1 illustrating a somewhat different form of the invention.

Fig. 5 is a transverse section similar to Fig. 3 of plaster board made with the coverings shown in Fig. 4.

45 Fig. 6 is a perspective view similar to Fig. 1 illustrating a slight modification of the construction shown in Fig. 1, and

Fig. 7 is a section similar to that shown in Fig. 3 showing the plaster board equipped 50 with the coverings illustrated in Fig. 6.

Like reference characters refer to like parts in the different figures of the drawing.

The body 1 of cementitious material may be of any desired width and length and it is 55 relatively thin. On opposite sides of this body coverings of fibrous material, prefer-

ably certain grades of paper, are placed. The upper covering sheet 2 at its side edges is bent inwardly at right angles to make the edge section 3, which, at its edge, is cut to 60 provide alternate tongues and recesses 4 and 5, the tongues 4 extending downwardly from the portion 3 of the paper covering. This is the construction at each edge of the plaster board.

65 The lower covering 6 has its edges turned upwardly at right angles to make the section 7 which, at its edge, is also cut to form alternate upwardly projecting tongues 8 and recesses 9 between the tongues. The position of the tongues and recesses on the two opposed edge sections 3 and 7 of the coverings is such that the tongues 4 are directly opposite the recesses 9 and, similarly, the tongues 8 are directly opposite the recesses 5.

70 When applied to the body 1 of plaster it is evident that tongues 4 passing downwardly into the recess 9 may be bent inwardly so as to lie against the inner side of the part 7 80 below said recesses 9 and, in like manner, the tongues 8 may pass into the recesses 5 and thence be bent inwardly so as to lie within the inner sides of the edge section 3 of the upper covering sheet 2. This is fully shown 85 in Fig. 3 and it is clear, as thus constructed, the tongues 4 and 8 are held in interlocked engagement, the plaster body 1 bearing against said tongues, it being understood that in the process of making the plaster board the 90 covering sheets 2 and 6 with their edge portions 3 and 7 having the tongues 4 and 8 are applied while the plaster body is still in plastic state and it is rolled or otherwise worked into position that it presses against 95 said tongues, the paper covering cementing to the plaster body as it sets and hardens.

95 The edge of the board thus made is shown in Fig. 2 and, if it is desired, a strip of paper 10 may be glued or otherwise cemented 100 to the edge of the board so as to cover the joints which would appear otherwise. This, however, is not necessary and my invention is in no sense limited to the addition of the covering strip 10, as shown in Figs. 2 and 3. 105

In Figs. 4 and 5 another form of the invention is shown in which the tongues 4 are of greater length and have their end portions turned inwardly at right angles, as indicated at 11. The tongues 8 also are of 110 greater length and have their upper end portions turned inwardly at right angles,

as indicated at 12. When the board is made with coverings of this character applied to the body 1 it will be evident that the tongues 11 and 12 extend inwardly along the inner sides of the lower and upper covering sheets 6 and 2, respectively, as shown in Fig. 5.

In Figs. 6 and 7 the construction shown is very similar to that shown in Figs. 1 and 3, the only difference being that the tongues 10 4^a and 8^a are shorter than the tongues 4 and 8 and the recesses 5^a and 9^a are correspondingly shallower. The section of the board formed with coverings of this character is shown in Fig. 7 and it is evident that the tongues 15 4^a and 8^a do not extend downwardly and upwardly as far as the tongues 4 and 8 in the construction shown in Fig. 3, but that an interlocking of the opposed covering sheets of paper at the edges of the board is made 20 and a complete covering of the board edges is effected.

This construction of plaster board is simple and effective and is very easily produced without any involved process of manufacture. The invention is defined in the appended claims and is to be considered as comprehensive of all forms of structure coming within their scope.

I claim:

1. Plaster board of the character described comprising a flat body and a covering sheet on each face of the body, said sheets at an edge of the body being folded toward each other and against said edge of the body, the edges of said sheets being formed with alternate tongues and recesses between said tongues, the tongues on the sheets entering the recesses on the opposite sheets and being bent inwardly and extending beyond the bot-

toms of said recesses at the inner sides of 40 the edge portions of said covering sheets.

2. Plaster board of the character described comprising a flat body and a covering sheet of material on each face of the body, said sheets at the opposite edges of the body 45 being folded toward each other and against the edges of the body and each being provided with projecting tongues separated by recesses, said tongues having interlocking engagement with each other and the opposite 50 covering sheets.

3. Plaster board of the character described comprising a flat body of cementitious material, and a covering sheet on each face of the body, said sheets at each edge of the body 55 being folded toward each other and each being provided with projecting tongues separated by recesses, the tongues on one sheet passing between tongues on the opposite sheet and lying against the inner sides of the edge 60 portion of said sheets beyond the bottoms of said recesses.

4. Plaster board of the character described comprising a flat body, and a covering sheet on each face of the body, said sheets at an 65 edge of the body being folded toward each other and against said edge of the body, the edges of said sheets being formed with alternate tongues and recesses between said tongues, said tongues on one sheet passing 70 between the tongues on the opposite sheet and lying against the inner sides of the edge portion of said sheets and at their ends being bent inwardly substantially at right angles so as to lie above and below the body 75 adjacent the edges of said body.

In testimony whereof I affix my signature.
CARL ABSMEIER.
